DRAWER PULL AND LABEL HOLDER
Vincent J. Cafiero, Irvington, N.Y., assignor to
Art Metal, Inc., Jamestown, N.Y.
Filed Oct. 20, 1965, Ser. No. 498,895
4 Claims. (Cl. 40—325)

This invention relates to office equipment, and more particularly to a combination label holder and hand-hold or "pull" device such as is useful in connection with a filing drawer, cabinet door or cover, or the like.

It is a primary object of the present invention to provide a combination device as aforesaid which is structurally simple and artistically attractive while at the same time providing a hand-hold of utmost convenience to the user.

Another object is to provide an improved device as aforesaid which also features the provision of an improved label holding arrangement whereby to present the label to view in an improved manner and also permitting interchange of labels with ease and facility.

Other objects and advantages of the invention will appear from the specification hereinafter and the accompanying drawing wherein:

FIG. 1 is a front perspective view of a cabinet or the like having a sliding drawer and a bottom hinged door panel, each equipped with a combination label holder and pull device of the invention;

FIG. 2 is a fragmentary, close-up, front elevational view of a device of the invention as shown in FIG. 1;

FIG. 3 is a rear, elevational view of the structure of FIG. 2;

FIGS. 4 and 5 are sectional views taken as suggested by lines 4—4 and 5—5 of FIG. 6;

FIG. 6 is a fragmentary sectional view, on enlarged scale, taken as suggested by line 6—6 of FIG. 1; and

FIG. 7 is an "exploded" perspective view of the two components of the device of the invention, as shown in the drawing herewith.

As illustrated herein by way of example, the device of the invention is adapted to be mass-produced by simple casting or molding processes, to comprise a pair of components adapted to be slip-fitted together and then inserted into an apertured portion of the drawer header or door panel (as the case may be); and then fastened in place and in assembled relation by means of simple machine screws. Thus, referring more particularly to FIGS. 4, 5, 6, the panel member upon which the device is to be mounted may comprise a sheet metal construction including a front plate 10 and a back plate 12; the front plate 10 having rearwardly turned marginal flanges as indicated at 14. Thus, when the front and back plates are relatively assembled as shown in FIG. 6, they provide a dual-walled panel construction. The front plate is rectangularly apertured as indicated at 16, and the back plate is apertured as indicated at 18.

The device of the invention comprises, as perhaps is best shown in FIG. 7, a front frame member designated generally at 20 and a back base member designated generally at 22. The front frame 20 includes a rectangularly shaped open window portion 24 margined by a rim 26 dimensioned to protrude through the aperture 16 of the front plate when the parts are in assembled position, thereby finishing off the front aperture of the installation. Integrally formed with the frame part at its opposite ends are ear portions 28, 28, which are apertured as indicated at 29 to accommodate mounting screws as indicated at 30—30. The main body portion of the frame member is recessed or "socketed" inwardly from the rear thereof. The back base member 22 comprises a generally flat rectangularly shaped piece 32 having a forwardly protruding

2

sloping land portion 34 formed integrally therewith to provide an inclined surface against which a label card or the like as indicated at 35 may recline when the device is assembled as shown in FIG. 6. Note that when the 5 parts are in assembled relation the protruding land portion 34 slip-fits into the rear "socketed" portion of the front frame member. The back base member 32 is also apertured at its opposite ends as indicated at 37, 37 so as to accommodate the mounting screws 30, 30 for assembly 10 of the parts and mounting on the unit on the panel, as shown in FIGS. 4, 5.

To accommodate the mounting screws 30, 30, simple Z brackets 40, 40, or the like may be employed as shown in FIGS. 4, 5; the Z brackets being spot-welded or 15 otherwise suitably fixed to the panel rear plate 12. Or, in lieu thereof, any other form of mounting connection may be provided. As shown in FIGS. 6, 7, the base member 22 is slightly recessed as indicated at 42 along its upper edge in the region where the land surface 34 intersects the plane of the back surface of the base member, whereby to provide a horizontally extending upwardly-opening slot into which the label 35 may be downwardly slip-fitted into operative position as shown in FIG. 6. Thus, 20 it will be appreciated that when the device of the invention is assembled on a filing drawer header or door panel or the like as illustrated and described hereinabove, an identification label for the cabinet contents may be simply slip-fitted from the rear of the panel downwardly through the slot as indicated at 18 (FIG. 6) into a firmly held reclining position against the inclined land surface 34.

It is also a particular feature that the top sill portion of the front frame member 20 is upwardly recessed as indicated at 45 (FIG. 6), thereby providing interiorly thereof 35 an upwardly extending pocket across the width of the device into which the finger tips of the user may be inserted, thereby providing a hand-hold or "pull" device for the drawer or door device, as the case may be. The label card to be inserted in the mechanism of the 40 invention is preferably provided with a transparent protective device, such as for example a clear plastic or varnish coating. Or, a separate transparent sheet of plastic, celluloid or the like may be disposed to lie in front of the label card.

Thus it will be appreciated that the device of the invention, when assembled in a drawer header or the like, presents to view in a slightly upwardly inclined manner the label plate identifying the contents of the 45 drawer; and that in order to pull the drawer open the user simply slip-fits his finger tips upwardly into the recess behind the top edge of the open window portion, and then pulls outwardly thereon. Whereas the device is illustrated and described hereinabove by way of example to be formed of cast or molded metal, it will of course be understood that it may with equal facility be molded of plastic; or, alternatively, may be fabricated 50 of any other material such as sheet metal, or the like.

Also, it is to be understood that whereas only one form 55 of the invention has been illustrated and described in detail hereinabove, it will be understood that various changes may be made therein without departing from the spirit of the invention or the scope of the following claims.

I claim:

1. A combination label holder and pull device for installation in an apertured portion of a movable door panel, drawer header, or the like; said device comprising a front frame member and a back base member slidably interfitting to comprise a mutually reinforcing unit providing a label-holding slot-like space therebetween, said front frame member comprising a socketed main body portion

of frame-like form having attachment means extending laterally therefrom and a centrally disposed label viewing aperture, said back base member having attachment means extending laterally thereof for assembled registry with the attachment means of said frame member and also including a main body portion comprising a forwardly protruding flat land surface portion projecting into the socketed portion of said framing member behind said frame member aperture and thereby providing means for supporting a label viewable through said frame member aperture when said parts are in assembled relation.

2. A combination label holder and pull device for installation in an apertured portion of a movable door panel, drawer header, or the like; said device comprising a front frame member and a back base member slidably interfitting to comprise a mutually reinforcing unit providing a label holding slot-like space therebetween, said front frame member comprising a socketed main body portion of frame-like form having attachment means extending laterally therefrom and a centrally disposed label viewing aperture, said back base member having attachment means extending laterally thereof for assembled registry with the attachment means of said frame member and also including a forwardly protruding main body portion in the form of an obliquely disposed flat land surface projecting into the socketed portion of said framing member behind said frame member aperture and thereby providing means for supporting a label in vertically inclined attitude and viewable through said frame member aperture when said parts are in assembled relation.

3. A combination label holder and pull device for installation in an apertured portion of a movable door panel, drawer header, or the like; said device comprising a front frame member and a back base member slidably interfitting to comprise a mutually reinforcing unit providing a label holding slot-like space therebetween, said front frame member comprising a main body portion of

frame-like form having attachment means extending laterally therefrom, said back base member having attachment means extending laterally thereof for assembled registry with the attachment means of said frame member and also including a main body portion comprising a vertically inclined flat land surface portion projecting into said frame member body portion and thereby providing means for supporting a label viewable through said front frame member when said parts are in assembled relation.

10 relation.

4. A combination label holder and pull device for installation on a movable door panel, drawer header, or the like; said device comprising a front frame member and a back base member slidably interfitting to comprise a
15 mutually reinforcing unit providing a label holding slot-like space therebetween, said front frame member comprising a socketed main body portion having attachment means extending laterally therefrom and a centrally disposed label viewing aperture, said back base member in-
20 cluding a main body portion having attachment means extending laterally thereof and including a forwardly protruding vertically inclined flat land surface portion projecting into the socketed portion of said framing member behind said frame member aperture and thereby providing
25 means for supporting a label viewable through said frame member aperture when said parts are in assembled relation.
